(57) **CLAIM**

The ornamental design for a roof duct cap assembly, as shown and described.

DESCRIPTION

FIG. 1 is a perspective view of a first embodiment of a roof duct cap assembly, in a closed state, showing my new design;

FIG. 2 is a front elevation view thereof;

FIG. 3 is a rear view thereof;

FIG. 4 is a right-side view thereof;

FIG. 5 is a left-side view thereof;

FIG. 6 is a top plan view thereof;

FIG. 7 is a bottom plan view thereof;

FIG. 8 is a cross section view thereof taken along line 8-8 of FIG. 3;

FIG. 9 is an exploded perspective view of FIG. 1;

FIG. 10 is a perspective view of a second embodiment of the roof duct cap assembly, in a closed state;

FIG. 11 is a front elevation view thereof;

FIG. 12 is a rear view thereof;

FIG. 13 is a right-side view thereof;

FIG. 14 is a left-side view thereof;

FIG. 15 is a top plan view thereof;

FIG. 16 is a bottom plan view thereof;

FIG. 17 is a cross section view thereof taken along line 17-17 of FIG. 12;

FIG. 18 is an exploded perspective view of FIG. 10;

FIG. 19 is another exploded perspective view of FIG. 10, in which cap is shown inverted;

FIG. 20 is a perspective view of a third embodiment of the roof duct cap assembly, in a closed state;

FIG. 21 is a front elevation view thereof;

FIG. 22 is a rear view thereof;

FIG. 23 is a right-side view thereof;

FIG. 24 is a left-side view thereof;

FIG. 25 is a top plan view thereof;

FIG. 26 is a bottom view thereof;

FIG. 27 is a cross section view thereof, taken along line 26-26 of FIG. 23;

FIG. 28 is an exploded perspective view of FIG. 20; and,

FIG. 29 is another exploded perspective view of FIG. 20.
